UNITED STATES PATENT OFFICE.

CHARLES F. RUBEL AND FRANK KUCERA, OF CHICAGO, ILLINOIS, ASSIGNEES TO UNION SPECIAL MACHINE COMPANY, OF CHICAGO, ILLINOIS, A CORPORATION OF ILLINOIS.

SEWING MACHINE FOR CORDING.

Application filed July 12, 1926. Serial No. 121,918.

The invention relates to new and useful improvements in a sewing machine and more particularly to a sewing machine for forming a corded seam.

5 An object of the invention is to provide a sewing machine having two spaced needles and a cooperating thread-carrying looper with means associated with the looper for positioning the needle loop adjacent the heel 10 of the looper so that the looper thread loop is entered only by the needle adjacent the point of the looper.

A further object of the invention is to provide a machine of the above type with 15 means whereby the fabric being stitched is formed with a ridge between the stitching needles and a cord is fed into the recess on the under face of the material formed by said ridge, which cord is secured to the fabric so as to make a permanent ridge in the 20 material by the needle threads and the looper thread, which looper thread crosses said cord and secures it to the material.

These and other objects will in part be 25 obvious, and will in part be hereinafter more fully disclosed.

In the drawings which show by way of illustration one embodiment of the invention:

30 Fig. 1 is a front view of a portion of a machine embodying the improvements with parts broken away to show the mechanism in rear thereof.

Fig. 2 is a plan view of the parts beneath 35 the cloth plate.

Fig. 3 is a vertical sectional view through the cloth plate and the parts beneath the same on the line 3—3 of Fig. 1.

40 Fig. 4 is a vertical sectional view through the cloth plate and the parts beneath the same on the line 4—4 of Fig. 1.

Fig. 5 is a detail in section showing the connection between the shaft which supports the loop positioning device and the lever 45 which moves the same endwise.

Fig. 6 is an enlarged sectional view through the throat plate, presser foot, feed dog, looper and thread positioning devices, taken substantially on the line of feed.

50 Fig. 7 is a plan view of the throat plate, feed dog and cloth plate adjacent the throat plate.

Fig. 8 is a sectional view on the line 8—8 of Fig. 7.

55 Fig. 9 is a view showing in diagram and

section the throat plate, the stitching element and the presser foot with the needles all the way up.

Fig. 10 is a view similar to Fig. 9, but showing the needle thread loops positioned 60 so that the needle at the left only will enter the looper thread triangle.

Fig. 11 is a plan view on a very large scale showing the fabric, the cord, the stitches and the stitching element at the 65 time when the needle is positioned as shown in Fig. 10.

Fig. 12 is a bottom plan view of the finished seam.

Fig. 13 is a sectional view on the line 70 13—13 of Fig. 11.

The invention is directed broadly to a sewing machine for forming a corded seam wherein a cord is placed on the under face of the fabric in a recess formed by a ridge 75 in the material and is secured to the material by needle thread loops and a looper thread loop, the looper thread loop passing from one row of needle thread loops to the other and serving as the sole means for covering the cord and holding the cord both to the material and the ridge in the material formed by the cord.

It is desirable that the stitching threads shall be so formed and arranged that when 80 the seam is put under strain, during lasting for example, the threads will not give, but will hold the ridge in the material precisely in the manner that it is originally formed.

In order to carry out this arrangement of 85 90 the threads it is desirable that the needle thread loops shall be directly opposed to each other in the formed seam and that the thread loops shall be joined by a looper thread loop passing through opposing needle loops 95 and secured by one needle thread loop only. The needle thread loop which secures the looper thread loop is on the opposite side of the seam from the laying of the looper thread. The thread carrying needles and 100 the thread carrying looper are of the usual construction.

Associated with the thread carrying looper is a loop positioning finger which engages the needle thread loop of the needle nearest the heel of the looper when the looper is in the needle thread loop, and forces said needle thread loop toward the left-hand needle so that when the right-hand needle passes down beneath the fabric, it will not pass 110

into the looper thread loop, but the looper thread triangle formed by the looper thread loop and the needle thread loop of the left-hand needle will be entered only by the left-hand needle.

Referring more in detail to the drawings, the machine consists of a bed plate 1 carrying a cloth plate 2 provided with a throat plate 3. Overhanging the cloth plate 2 is an arm 4 in which a needle bar 5 reciprocates. Said needle bar carries two needles 6 and 7. Cooperating with the needles beneath the work support is a thread carrying looper 8. This looper 8 is mounted on a looper carrier 9 which is pivoted at 10 to a looper support 11. The looper carrier is oscillated on its pivot by a link 12 and the looper support is oscillated to give a needle avoiding movement to the looper by an arm 13 which is fastened to the supporting shaft for the looper support, and which arm cooperates with an eccentric 14 on the main shaft 15.

The material is fed across the work support by means of a feed dog 16. This feed dog is carried by a feed bar 17 attached to a feed rocker 18. The feed rocker 18 is oscillated by an arm 19 connected in the usual manner to a crank on the forward end of the main shaft 15. The feed bar is raised and lowered by a cam 20 on the main shaft 15. Cooperating with this feed dog 16 is an upper feed dog 21 carried by a vertically disposed feed bar 22. The feed bar 22 has an oscillating connection at 23 with the overhanging arm 4 and is raised and lowered and moved back and forth by a mechanism indicated diagrammatically at 24 in Fig. 1 of the drawings. All of the above mechanism is of the usual construction and further detailed description is not thought necessary.

The material is held on the work support by a presser foot 25 carried by a presser bar which is yieldably forced downwardly by a spring 27. The upper feed dog 21 is provided with two spaced members cooperating with the outer sections of the feed dog 16 and located between the spaced sections of the upper feed dog for the presser foot 25. The presser foot 25 is provided with two spaced sections 26, 26. The throat plate 3 is provided with an upstanding rib 27 located in the space between the sections 26, 26 of the presser foot. This rib 27 has a longitudinal passage 28 extending therethrough. The rib is for the purpose of forming a ridge in the material and the groove 28 is for the purpose of directing a cord beneath the material and into the recess formed by the ridge.

Before proceeding further with the description of the machine, the article formed on the machine will be described. This article consists of a fabric F. The fabric F is formed into a ridge f and the cord c is

laid on the under face of the material and in the recess formed by the ridge (see Figs. 12 and 13). The needle thread n is formed into a series of thread loops n¹ which are passed through the material at one side of the ridge f. The needle thread n² is formed in the series of loops n² which are passed through the material at the other side of the ridge. The thread loops n¹ and n² are directly opposed to each other. The looper thread l is formed into a series of loops l¹ and these loops l¹ pass through first the needle thread loop n¹ and then the directly opposed needle thread loop n². The looper thread loop is locked by the needle thread loop n² of the next formed stitch.

With this understanding of the article, the remainder of the mechanism of the machine will be described and the operation thereof.

As the material F passes through the machine beneath the presser foot 25 and beneath the upper feed dog 21, the rib 27 will bend the fabric so as to form a ridge f. The cord c which may be of any desired material is led through the passage 28, and this places the cord in the recess in the under face of the fabric formed by the ridge f. This ridge is so disposed that the needle 6 carrying the needle thread n passes down alongside of the ridge f and along one side of the cord c, while the needle 7 carrying the needle thread 2 passes down alongside of the other side of the ridge f and the other side of the cord c. These needles 6 and 7 lie in a plane cutting the line of feed at right angles, and therefore the needle thread loops n¹ and n² are directly opposed. The looper 8 passes through these thread loops as shown in Figs. 9 and 10. Cooperating with the looper 8 is a thread positioning finger 29 carried by an arm 30. This arm 30 is rigidly secured to a shaft 31, which shaft 31 is mounted in bearings 32, 32 secured to the bed plate of the machine. The shaft 31 carries a forked head 33 in which is mounted a vertical shaft 34 slabbed to receive the forked end of an arm 35 which is adjustably attached to a lever 36. A screw 37 is provided for clamping the forked end of the arm 35 against the slabbed sides of the vertical shaft 34. The lever 36 (see Fig. 3) is mounted on a vertical stud 38 and is oscillated thereon by an eccentric strap 39 cooperating with an eccentric 40 on the main shaft 15 (see Fig. 2). When the lever 36 is oscillated it will move the shaft 31 carrying the support for the loop positioning finger in an endwise direction, and this will move the loop positioning finger lengthwise of the looper as the shaft 31 is parallel to the axis of the looper support and at right angles to the axis of oscillation of the looper.

The support 30 for the positioning finger

is shown in side view in Fig. 4. This support projects rearwardly from the shaft 31 and is provided with a forked portion 41 which cooperates with an eccentric 42 on the 5 main shaft 15. At the upper end of the support 30 there is a bracket 43 which is secured to the support 30 by suitable bolts 44. The positioning finger 29 is clamped to the bracket 43 by a set screw 45. The eccentric 42 will oscillate the shaft 31 about its longitudinal axis and this will move the 10 positioning finger 29 in a direction across the looper.

The parts are so timed that when the looper is retracted after it has entered the needle thread loop, as shown in Fig. 9, the positioning finger 29 will move forward and across the body of the looper engaging the needle thread loop n^1 , as shown in Fig. 10, and 15 forces said loop toward the point of the looper and to the left of the right-hand needle as viewed in Fig. 10. By this positioning of the needle thread loop n^1 the needle 6 will not pass into the looper thread 20 loop, while the needle 7 will pass to the left of both of the needle thread loops and into the thread triangle formed by the needle thread loop n^3 , the looper and the looper thread leading from the point of the looper 25 to a previous stitch. In other words, this positioning finger so positions the needle thread loop of the right hand needle as viewed in Figs. 9, 10, and 11, that the left hand needle only enters the looper thread 30 loop.

The result is the article described above; that is, an article wherein the cord is held to the material solely by the looper thread loop passing through the needle thread loops, 40 and furthermore the looper thread loop is anchored or secured to opposing needle thread loops, and therefore the strands of the looper thread after passing through the right hand needle loop cross the cord in a 45 direction at right angles to the length of the cord. The strands for the looper thread loop then pass through the other needle thread loop, and the looper thread loop is secured by the needle thread loop on the 50 same side of the cord that the loop issues from the needle thread loops.

By this arrangement a seam is formed wherein any strain on the seam comes lengthwise of the looper threads and this 55 prevents the needle thread loops from drawing apart, or the ridge flattening out.

The article produced on the improved machine is therefore especially adapted for making moccasins, or in the construction of 60 shoes where, after the material has been corded either for the purpose of ornamentation or for the purpose of imitating a seam, the lasting of the shoe does not in any way disturb the corded seam.

65 It will be noted from the above that the

thread positioning finger has four motions. It not only moves endwise of the looper, but moves crosswise of the looper. The timing of this positioning finger is such that it moves across the looper and into engagement with 70 the thread loop therein, and then moves the thread loop forward on the looper. After the needle is well down into the thread triangle then the thread finger moves away from the looper or returns for the beginning 75 of its cycle of movement.

It will be understood that the stitch-forming mechanism may be used in other types of machines than in a cording machine, and therefore the invention is not limited to the 80 specific embodiment illustrated.

What is claimed as new is:

1. A sewing machine including in combination two spaced needles, a thread carrying looper cooperating with both needles, a thread positioning finger and means for operating said thread positioning finger whereby said finger moves across the looper into engagement with the needle thread loop thereon adjacent the heel of the looper, and moves said loop forward on the looper when the needles descend so that the looper thread loop is entered only by the needle adjacent the point of the looper. 90

2. A sewing machine including in combination a cloth plate, a rib on said cloth plate, a presser foot cooperating with said rib for forming a ridge in the material being stitched, a pair of needles located one on each side of said rib, a thread-carrying looper cooperating with said needles, a thread positioning finger and means for operating said finger, whereby said finger is moved across the looper and then forward against the needle thread loop thereon adjacent the heel of the looper for moving said loop forward on the looper so that the looper thread loop is entered only by the needle adjacent the point of the looper. 100

3. A sewing machine including in combination a work support, a rib on said work support, a presser foot cooperating with said rib to form a ridge in the material being stitched, said rib having a passage therethrough for guiding a cord into the recess formed in the fabric being stitched by said rib, spaced needles, one on each side of said ridge, a thread-carrying looper cooperating with both needles, a thread positioning finger and means for moving said finger into engagement with the needle thread loop adjacent the heel of the looper for moving said loop forward so that only the needle adjacent the point of the looper will enter the looper thread loop. 110

4. A sewing machine including in combination a feeding mechanism, needles spaced from each other and located in a plane at right angles to the line of feed, a thread-carrying looper cooperating with said 120

needles, and means associated with said looper for engaging the needle thread loop on the looper adjacent the heel of the looper for moving said loop forward on the looper so that the needle adjacent the point of the looper only will enter the looper thread loop.

5. A sewing machine including in combination a feeding mechanism, needles spaced from each other and located in a plane at right angles to the line of feed, a thread-carrying looper cooperating with said needles, means associated with said looper for engaging the needle thread loop on the looper adjacent the heel of the looper for moving said loop forward on the looper so that the needle adjacent the point of the looper only will enter the looper thread loop, and means for guiding a cord beneath the fabric and between the paths of the needles whereby said cord is secured to the fabric by the stitching threads only.

6. A sewing machine including in combination a feeding mechanism, needles spaced from each other and located in a plane at right angles to the line of feed, a thread-carrying looper cooperating with said needles, means associated with said looper for engaging the needle thread loop on the looper adjacent the heel of the looper for moving said loop forward on the looper so that the needle adjacent the point of the looper only will enter the looper thread loop, means for forming a ridge in the fabric being stitched between the needles, and means

for guiding a cord beneath and into the recess formed by said ridge whereby said cord is secured to the fabric and the ridge maintained therein solely by the stitching threads. 35

7. A sewing machine including in combination a thread-carrying looper, a thread positioning finger associated with said thread-carrying looper, means for supporting said thread positioning finger and giving thereto a movement across the looper, thence forwardly on the looper, thence laterally 40 away from the looper, and thence rearwardly alongside of the looper to its initial starting position, said stitch positioning finger being adapted to engage a needle loop on the looper and move the same forward 45 toward the point of the looper.

8. A sewing machine including in combination, two spaced needles, a thread carrying looper cooperating with both needles, means for giving said thread carrying 55 looper a movement into and out of the needle thread loops, means for giving said looper a needle avoiding movement, and means for moving the needle thread loop adjacent the heel of the looper forward on 60 the looper when the needles descend so that the looper thread loop is entered only by the needle adjacent the point of the looper.

In testimony whereof, we affix our signatures.

CHARLES F. RUBEL.
FRANK KUCERA.
